UNITED STATES PATENT OFFICE.

FRIEDRICH DESSAUER, OF ASCHAFFENBURG, GERMANY.

APPARATUS FOR TAKING PHOTOGRAPHS WITH RÖNTGEN RAYS.

1,096,691.

Specification of Letters Patent.

Patented May 12, 1914.

Application filed November 8, 1909. Serial No. 526,795.

To all whom it may concern:

Be it known that I, FRIEDRICH DESSAUER, engineer, a subject of the King of Bavaria, residing at Aschaffenburg-on-the-Main, in the Kingdom of Bavaria, German Empire, have invented certain new and useful Improvements in Apparatus for Taking Photographs with Röntgen Rays, of which the following is a specification.

10 This invention relates to an apparatus for making instantaneous X-ray photographs and has particular reference to an improvement in means for exposing photographic plates used in connection with X-ray photography.

15 The object in view in this connection is to construct an X-ray photographing apparatus which is capable of effecting an extremely rapid exposure of the photographic 20 plate as well as to simplify the structure of such a mechanism.

With this object in view, my invention will hereinafter be fully set forth and described, reference being had to the accompanying drawing, in which one embodiment 25 of my invention is shown.

For some time efforts have been made to shorten the length of time required for taking X-ray pictures, so as to render it possible 30 to take a truly instantaneous picture. In some cases, so-called "instantaneous" pictures, were taken in from one to ten seconds, and exposures of as much as twenty seconds have been considered as instantaneous.

35 In a few isolated cases pictures have been taken in less than one second, ranging in time from one quarter to one twenty-fifth of a second. Even the latter cases, however, do not really come under the head of instantaneous exposures, and one can only call 40 an exposure "instantaneous", when the period of light, with reference to the rapidity of the movement of the object to be photographed, such, for instance, as the beating

45 heart, or voluntary or involuntary movements of the muscles, is of short duration. Thus, a practical instantaneous exposure is one which is made in, at the most, one fiftieth of a second, and generally ranges from 50 one hundredth to one three-hundredth part of a second. In radiograms taken with the apparatus described herein the outlines of the beating heart show absolutely sharp on the plate.

55 So-called instantaneous pictures taken by the old methods, and the times of exposure

of which range from one to twenty seconds, have almost invariably been secured by apparatuses in which were used a direct current powerful induction coil and Wehnelt 60 interrupter or less frequently, a mercury interrupter, the secondary high tension alternating current being transformed into high tension continuous current.

The present invention, by which pictures 65 of 1/100 to 1/300 second exposures have been made, is based on the single excitement of the secondary coil of a transformer by the interruption of the primary continuous current, and a high tension transformer is used 70 for that purpose, said transformer being constructed similar to a simple induction coil. Furthermore, it uses a continuous current, but, in contradistinction to other apparatuses, no continuously operating make 75 and break is employed. The use of an interrupter makes an instantaneous exposure impossible, and instantaneous photographs 80 are successful with the herein described apparatus, chiefly, because a single impulse of discharge is used, the duration of which, with the high potential transformer lies between 1/50 and 1/300 of a second.

In the accompanying drawings, which 85 represent one form of the invention, *a* is the direct current transformer, and has one pole of the primary coil connected to one side of a current source *s*. A condenser *b* might be connected with one pole in contact with the other terminal of the primary coil of the 90 transformer *a*, and is furnished of suitable size so that when the primary circuit is broken, the strength of the discharge of current can be raised by the diversion of the current to said condenser and thence back 95 over the line, producing on the secondary coil an induced current of a very high voltage capable of ionizing the X-ray tube.

In the circuit established between the primary coil of the transformer *a*, the current source *s* and the condenser *b* is a switch *c*. Said switch is, or may be, of any type and may consist of a switch arm *c'* and a leaf which may enter the fixed contact members; the latter being connected to the condenser 105 terminal. Also connected in parallel with said condenser and the transformer *a* is a fuse *d'* which is constructed and tested so that its fusing and load curve are accurately known quantities. The fuse is made of suitable length and is embedded in gypsum or some similar substance, those substances be- 110

ing especially suitable which can be pulverized suddenly. In order to promote the breakage and the instantaneous extinction of the spark induced by the sudden burning out, other materials may be added to the composition of the coating. For example, substances containing moisture, such as clay, glue, and moist earths, in which, when the fuse is heated, steam is generated to aid in bursting the cartridge, also emery powder, fine sand or a small quantity of gun-powder will aid in extinguishing the spark.

It is very important that the fuse bursts exactly at the moment, *i. e.* not earlier nor later, when the magnetizing current has attained that maximum strength which is necessary in order to obtain the desired effect. The fuse thus insures that on the one hand the current strength required is not exceeded, and on the other hand the circuit is not interrupted before the current has attained its critical height. The thickness of the fuse is adapted to the desired effect.

When the switch *c* is closed, the current in the primary circuit becomes quickly and continuously stronger in overwhelming the inductive reactance in the transformer *a*, until the fuse is consumed. As above stated, the fusing and load curves of the fuse are accurately determined quantities, so that the interval between the closing of the switch *c* and the burning out of the fuse will be absolutely known. The consumption of the fuse must be effected as quickly as possible, and for this reason, the fuse is made of suitable length and is incased in impermeable material. In this way, a very high breaking velocity during the interruption will be insured and the primary breaking contact self induction spark be rapidly extinguished and the secondary breaking contact induction attain an exceedingly high potential. For each exposure, a new fuse is inserted in the circuit. Thus, it is obvious that the solution of the problem of instantaneous X-ray photography, as contemplated in this invention, depends on the possibility of a momentary large current, under the pro-

tection of the circuit current against excessive overloading, and the principal feature of this invention lies in this, that after the switching on of the current, a forceful switching off is caused after a time which is equal to the necessary duration of the magnetizing current, and which allows a high 55 overloading without danger.

As already stated, it is possible to overload electric machines for a very short interval of time to the extent of a few hundred per cent., and by this apparatus, the overloading is carried out without danger to the machine, by the almost simultaneous opening of the circuit. The discharge current strength can be raised by the passage of a current of a sufficiently high strength 65 through the transformer so that any desired X-ray exposure can be taken by a single discharge impulse.

What I claim is:—

1. In an apparatus for taking instantaneous X-ray photographs, the combination of a direct current transformer having an X-ray tube connected to its secondary coil, a switch, a current source adapted to overload the primary circuit when said switch is closed, and means for automatically breaking the primary circuit when the latter is overloaded to create a single intense excitement of the secondary coil circuit. 70

2. In an apparatus and method for taking instantaneous X-ray photographs, the combination of a direct current transformer having an X-ray tube in circuit with the secondary thereof, a current source, a switch in the primary circuit and a fuse in the circuit adapted to be destroyed when said switch is closed, whereby the primary circuit is momentarily overloaded to induce a single intense excitement of the secondary coil. 75 80 85

In testimony whereof I affix my signature in presence of two witnesses.

FRIEDRICH DESSAUER.
